INVENTOR
WILLIAM NEUHAUS

BY ATTORNEYS

This invention relates to door knockers and more particularly to door knockers of the mechanical type for producing a series of rapid blows or knocks on a door.

UNITED STATES PATENT OFFICE

2,405,916

DOOR KNOCKER

William Neuhaus, Neillsville, Wis.

Application October 25, 1944, Serial No. 560,231

1 Claim. (Cl. 116—167)

1

This invention appertains to door knockers and more particularly to door knockers of the mechanical type for producing a series of rapid blows or knocks on a door.

One of the primary objects of my invention is to provide a door knocker having a novel and attractive form shaped to simulate the appearance of a woodpecker with means for rocking the head of the woodpecker against the door for producing the desired sound to attract the householder to the door.

Another salient object of my invention is to provide a door knocker in the form of a woodpecker having a pivotally mounted head with a forwardly extending bill for rapping on the door with means including a hand crank and a star wheel or ratchet for oscillating the head.

A further and more specific object of my invention is to provide a novel means for mounting the head on the body of the knocker and for normally urging the head and bill into engagement with the door.

A still further important object of my invention is to provide a door knocker of the above character which will be durable and efficient in use, one that will be simple and easy to manufacture and one which can be placed upon the market at a reasonable cost.

With these and other objects in view, the invention consists in the novel construction, arrangement and formation of parts, as will be hereinafter more specifically described, claimed and illustrated in the accompanying drawing, in which drawing:

Figure 1 is a longitudinal sectional view through my door knocker taken substantially on the line 1—1 of Figure 2 looking in the direction of the arrows and showing the knocker applied to a door.

Figure 2 is a sectional view taken at right angles to Figure 1 and substantially on the line 2—2 of Figure 1 looking in the direction of the arrows.

Figure 3 is a horizontal sectional view taken on the line 3—3 of Figure 1 looking in the direction of the arrows.

Referring to the drawing in detail wherein similar reference characters designate corresponding parts throughout the several views, the letter K generally indicates my door knocker and D, a door with which the same can be connected.

The knocker K, as stated, is formed to simulate a woodpecker and hence the knocker is painted and otherwise ornamented to carry out this simulation. As illustrated, the same includes an elongated body 5, preferably formed

from a solid block of material such as wood, but obviously the same can be formed from cast metal or pressed from sheet metal. The inner face of the body 5 has formed therein an inwardly extending cavity 6 in which is mounted the operating mechanism for oscillating the head 7 of the knocker. Communicating with the cavity 6 through the upper end of the body is a passageway 8. The head 7 carries a forwardly

extending broad bill 9 which normally projects beyond the inner face of the body for engaging the door D as will be later set forth. The bill 9 is preferably tapered toward its forward end, but the same terminates in a broad tapping face 10.

Formed on or secured to the head 7 is a depending neck 11 which extends into the cavity 6 through the passageway 8. The neck terminates in a pointed end 12 for a purpose which will also be later described. A pivot pin 13 connects the neck with the body 5 whereby the head is free to rock back and forth to permit the engagement of the bill with the door.

Particular attention is invited to the leaf springs 14 as the same form an important feature of my invention. The front ends of the springs 14 are secured as at 15 to the upper end of the body on each side of the neck 11 and the rear ends of the spring curve upwardly, as at 16 into engagement with the lower face of

the head 7 in rear of the pivot 13 and normally urge the head forwardly and the bill into engagement with the door.

Rotatably mounted in the body 5 below the neck 11 is a transversely extending shaft 17. Mounted upon the shaft for rotation therewith is a star or ratchet wheel 18 and this ratchet wheel is deposited within the cavity 6. The radially extending points 19 of the star are adapted to engage the pointed terminal 12 of

the neck 11. One end of the shaft protrudes beyond the body 5 and has connected therewith a handle or crank 20 to permit the rotation of the shaft by a person. In order to permit the easy fastening of the knocker to a door D, the inner

face of the body has secured thereto transversely extending straps or brackets 21 which protrude beyond the side face of the body. Screws 22 can extend through the straps and into the door for securing the knocker firmly to the door.

In operation of my knocker, the crank 20 is turned and the points 19 of the star wheel 18 will engage the lower end of the neck and move said lower end forwardly and the head 7 rearwardly away from the door against the tension

of the leaf springs 14. As the pointed terminal

of the neck 11 rides off of a point the spring will forcibly and quickly move the bill into engagement with the door for producing a rap. By turning the crank rapidly a series of quick raps can be produced which will formulate the noise made by a woodpecker. From the foregoing description, it can be seen that I have provided a door knocker of an exceptionally simple form which can readily take the form of a woodpecker and which will formulate the noise made by a woodpecker when the knocker is operating.

Changes in details may be made without departing from the spirit or the scope of my invention, but what I claim as new is:

A door knocker shaped to simulate a woodpecker comprising a body having an interior cavity, means carried by the forward face of the body for connecting the same to a support, said cavity opening out through the upper end of the

body, a transversely extending shaft rotatably carried by the body extending through the cavity, means for rotating the shaft, a wheel having radially extending points secured to the shaft for rotation therewith, a head on the upper end of the body having a depending neck extending into the cavity and having its lower end arranged in the path of the wheel points, a pivot pin rockably mounting the neck intermediate its ends on the body, leaf springs disposed on opposite sides of the neck having their forward ends secured to the upper end of the body and their rear ends curved upwardly and rearwardly into engagement with the head in rear of the pivot for normally urging the head forwardly, and a striking bill carried by said head and projecting forwardly therefrom.

WILLIAM NEUHAUS.
